UNITED STATES PATENT OFFICE

2,379,325

FREQUENCY MODULATION

Harry Tunick, Rye, N. Y., assignor to Radio Corporation of America, a corporation of Delaware

Original application August 29, 1941, Serial No. 408,738, now Patent No. 2,282,103, dated May 5, 1942. Divided and this application January 21, 1942, Serial No. 427,572

10 Claims. (Cl. 179—171.5)

This is a division of my copending application Serial No. 408,738, filed August 29, 1941, now U. S. Patent No. 2,282,103, dated May 5, 1942, in turn a continuation in part of my copending application Serial No. 310,495, filed December 22, 1939, now U. S. Patent No. 2,296,962, dated September 29, 1942.

My present invention relates to transmitters for producing and transmitting frequency modulated waves. One object of my invention is to provide improved apparatus for producing frequency modulated waves. Other objects, advantages and features of my invention will be apparent as the more detailed description thereof proceeds.

In the accompanying drawing, the single figure is a wiring diagram of a frequency modulation transmitter employing my present invention.

In the transmitting system illustrated in the drawing, the oscillator tube 900 may have either crystal 902 connected between the plate 904 and grid 906 or, as shown, the series tuned circuit 908. The latter is connected, by means of switch 910, between the plate 904 and grid 906. The screen grid 920 is supplied with voltage through radio frequency choke 922 by-passed by condenser 924. The plate 904 is supplied with plus voltage through choke 930 by-passed by by-passing condenser 932. Transformers 934 and 936 insert alternating signal voltages in the plate and screen voltage leads. These signal voltages are derived from potentiometer 940 connected to the secondary of transformer 942 whose primary is connected across the plates of push-pull amplifier 944 energized from audio or signaling amplifier 946.

Since like voltage changes applied to the screen 920 and plate 904 produce opposite effects on the frequency of oscillation of tube 900, transformers 936 and 934 are so poled as to oppositely swing the screen 920 and plate 904 in voltage in accordance with signal voltages derived from amplifier 946. The output circuit 950 of the oscillator 900 is fed to the limiter 952 which may be a power amplifier and/or frequency multiplier. The latter, represented by rectangle 952, is connected to and energizes the transmitting antenna 954.

Having thus described my invention, what I claim is:

1. A system for producing frequency modulated waves comprising an electron discharge device oscillation generator, said generator including a vacuum tube having a plate, a screen grid, a control grid and a cathode, a source of

modulating voltages and circuits for applying said modulating voltages oppositely to said screen grid and plate whereby the frequency of oscillations generated is varied in accordance with said modulating voltages.

2. In a frequency varying system, an oscillation generator having an anode, a cathode, a control grid and a screen grid, circuits interconnecting said electrodes whereby oscillations of substantially constant frequency are regeneratively generated, a source of modulating voltages, and means for applying said modulating voltages oppositely to the anode and screen grid whereby said oscillations are varied in frequency in accordance with said modulating voltages.

3. Apparatus as claimed in claim 1, characterized by the fact that the mean frequency of oscillations generated is controlled by a piezoelectric crystal.

4. A system for producing frequency modulated waves comprising an electron discharge device oscillation generator, said generator including a vacuum tube having a plate, a screen grid, a control grid and a cathode, a source of modulating voltages and circuits for applying said modulating voltages oppositely to said screen grid and plate whereby the frequency of oscillations generated is varied in accordance with said modulating voltages, a limiter for limiting the frequency modulated waves to waves of substantially constant amplitude, and a transmitting circuit for transmitting the limited waves.

5. A system for producing frequency modulated waves comprising an electron discharge device oscillation generator, said generator including a vacuum tube having a plate, a screen grid, a control grid and a cathode, a source of modulating voltages and circuits for applying said modulating voltages oppositely to said screen grid and plate whereby the frequency of oscillations generated is varied in accordance with said modulating voltages, a frequency multiplier for frequency multiplying the frequency modulated waves, and a transmitting circuit for transmitting the frequency multiplied frequency modulated waves.

6. In a frequency varying system, an oscillation generator having an anode, a cathode, a control grid and a screen grid, circuits interconnecting said electrodes whereby oscillations of substantially constant frequency are regeneratively generated, a source of modulating voltages, and means for applying said modulating voltages oppositely to the anode and screen grid

whereby said oscillations are varied in frequency in accordance with said modulating voltages, means for frequency multiplying and limiting the frequency modulated waves, and a transmitting circuit for transmitting the frequency multiplied and limited waves.

7. Apparatus for producing frequency modulated waves comprising an electron discharge device having plate, screen grid, control grid and cathode electrodes, a piezo-electric crystal connected to a pair of said electrodes, a high frequency output circuit connected to another pair of said electrodes, a source of modulating voltages and circuits for applying said modulating voltages oppositely to said screen grid and plate whereby the frequency of oscillations, normally controlled by said crystal, are varied in frequency in accordance with said modulating voltages.

8. Apparatus for producing frequency modulated waves comprising an electron discharge device having plate, screen grid, control grid and cathode electrodes, a piezo-electric crystal connected to a pair of said electrodes, a high frequency output circuit connected to another pair of said electrodes, a source of modulating voltages and circuits for applying said modulating voltages oppositely to said screen grid and plate whereby the frequency of oscillations, normally controlled by said crystal, are varied in frequency in accordance with said modulating voltages, a limiter for limiting the frequency modulated waves so produced to waves of substantially constant amplitude, and a transmitting circuit for transmitting the limited waves.

9. Apparatus for producing frequency modulated waves comprising an electron discharge device having plate, screen grid, control grid and cathode electrodes, a piezo-electric crystal connected to a pair of said electrodes, a high frequency output circuit connected to another pair of said electrodes, a source of modulating voltages and circuits for applying said modulating voltages oppositely to said screen grid and plate whereby the frequency of oscillations, normally controlled by said crystal, are varied in frequency in accordance with said modulating voltages, a frequency multiplier for frequency multiplying the frequency modulated waves so produced, and a transmitting circuit connected to said frequency multiplier for transmitting the frequency multiplied frequency modulated waves.

10. In a frequency varying system, an oscillation generator having an anode, a cathode, a control grid and a screen grid, circuits including a piezo-electric crystal inter-connecting said electrodes whereby oscillations of substantially constant frequency are regeneratively generated, a source of modulating voltages, and means for applying said modulating voltages oppositely to the anode and screen grid whereby said oscillations are varied in frequency in accordance with said modulating voltages, means for frequency multiplying and limiting the frequency modulated waves, and a transmitting circuit for transmitting the frequency multiplied and limited waves.

HARRY TUNICK.
